UNITED STATES PATENT OFFICE.

GEORGE W. VROMAN, OF HARTSHORNE, OKLAHOMA.

CROSS-TIE.

1,070,863.

Specification of Letters Patent. Patented Aug. 19, 1913.

Application filed December 28, 1912. Serial No. 739,118.

To all whom it may concern:

Be it known that I, GEORGE W. VROMAN, a citizen of the United States, residing at Hartshorne, in the county of Pittsburg and 5 State of Oklahoma, have invented certain new and useful Improvements in Cross-Ties, of which the following is a specification.

This invention relates to improvements in cross ties of the metallic type and the object 10 in view is to simplify the construction and improve the efficiency of such ties while reducing the initial expense as well as the expense of maintenance.

The invention comprises end sections and 15 a connecting gage bar therefor, each end section being formed of metal and provided with an angular recess for the reception of a rail-retaining spike.

The invention also comprises, as a new 20 article of manufacture, a section of tie having a relatively large surface area and pendent flanges spaced for forming grooves or pockets in the under portion of the section.

The invention still further comprises certain 25 other novel constructions, combinations and arrangements of parts as will be hereinafter specified and claimed.

In the accompanying drawing:—Figure 1 is a top plan view of a tie embodying the 30 features of the present invention, fragments of the rails being seen in position. Fig. 2 is a vertical section therethrough taken on the planes indicated by line 2—2 of Fig. 1. Fig. 3 is a similar section taken on the plane 35 indicated by line 3—3 of Fig. 1. Fig. 4 is a vertical section taken longitudinally of the track and transversely of the cross tie substantially on the plane indicated by line 4—4 of Fig. 1, the rail being seen in elevation. Fig. 5 is a fragmentary vertical section of a 40 slightly modified embodiment.

Referring to the drawing by numerals, 1, 1 indicate the end sections connected by the tie or gage bar 2, the bar 2 preferably 45 consisting of a flat bar extending in grooves 3 provided longitudinally of the respective sections 1, the flat bar at its ends being turned to form engaging hook portions 4 extending downwardly, each in a recess or 50 pocket 5 formed in the respective end section 1. Each end section 1 is composed of a relatively large thin flat body presenting a comparatively even flat upper face and having a central flange 6 pendent from and extending longitudinally of the under face of 55 the body, and side flanges 7, 7 similarly dis-

posed, the side flanges being connected at their ends by end flanges 8, thus producing pockets or grooves 9, 9 extending longitudinally and formed in the under face of the 60 body. The size of each section 1 may be varied according to the class of service required, but for the average use a section possessing a body three feet long and two feet wide, thus representing a square surface area of six feet, is effective and can be produced at a very reasonable expense proportionate to the service of which it is capable.

The gage bar 2 is preferably disposed centrally of the respective sections 1 and extends beneath the respective rail 10 which rests upon the section and beyond the same so that the ends of the bar 2 are exposed and may be inspected readily for determining whether the cross tie is in perfect condition. Spaced at each side of the bar 2 each of the sections 1 is formed with recesses in which are disposed cushioning blocks 11 preferably of hard wood, said blocks 11 being 80 adapted to carry the weight and to receive the vibrations of the rail 10. To adequately connect the rail to the cross tie, each section 1 is provided at the opposite sides of the rail with a vertical recess 12 which is of angular 85 formation, that is, bent longitudinally for producing an offset portion 13, but obviously each recess 12 may be otherwise or additionally curved or distorted.

Each recess is adapted for receiving a retaining spike or pin 14, and it is obvious that as the spike or pin is driven in place in the recess and is thus compelled to follow the contour of the recess, bending or buckling itself, it will be caused to be firmly 90 anchored in the respective section and as effectively retained in place as if wedged into position as in the instance of the use of an ordinary wooden cross tie. Each of the recesses 12 is disposed for insuring the 100 proper relative disposition of the respective pin 14 so that the head of the pin will lap the lower flange of the respective rail 10. As a matter of additional strength, a clip or flange-engaging plate 15 may be provided 105 for one or more of the spikes 14 of each section 1 and each plate has a flat or horizontal portion adapted to rest on the flat upper face of its respective section and an inclined portion adapted to rest upon the 110 upper face of the respective lower flange of the rail. Obviously when all of the spikes

14 are not provided with clips 15 those omitted will be those at the inner side of the rails.

Each of the recesses 12 is formed in a portion of the respective section 1 which is hardened, as for instance by being chilled about each recess 12, for insuring against any spike 14 chiseling its way in a direction other than that indicated by the recess, or as indicated in Fig. 5 each of the recesses, there denoted by the reference character 12', may be provided with a tubular liner 16 which of course is of material of requisite hardness for insuring the following of the recess by the retaining spikes. In the embodiment illustrated in Figs. 1 to 4 the recesses 12 extend downwardly through the web or flange 6, and in the embodiment illustrated in Fig. 5 the recesses 12' extend downwardly in the web or flange 6', said web being pendent from the body of the section 1' and the recesses being adapted to receive spikes 14' similar in construction and arrangement to the spikes 14.

Each end section 1 may be of steel or other suitable material and when formed of cast iron I prefer to harden the bottom or under face of the section by casting the same on a chill for increasing the strength directly beneath the rail.

Having thus described the invention, what is claimed as new is:

1. In a cross tie, the combination of end sections having longitudinal grooves, said end sections being spaced and alined endwise, and a gage bar connecting said end sections and extending within the grooves thereof and having means of anchorage to the end sections, each of the end sections being adapted to support a rail, the means

of anchorage of the bar being disposed outside the rail in position for ready inspection and the bar extending outside of the rail.

2. In a cross tie, the combination of end sections adapted to sustain rails, each formed with a recess outside its respective rail, and a gage bar having a hooked end portion and extending beneath the rails and having its hooked end portion engaging the recesses of the end sections outside of the respective rails for anchoring the sections together.

3. An end section for a metallic cross tie comprising a body of relatively soft metal adapted to have a rail sustained thereupon in a position extending transversely of the body, a central flange pendent from said body and extending longitudinally thereof, and side flanges spaced from the central flange and extending substantially parallel thereto, affording grooves between the central flange and side flanges, the under face of the body being hardened.

4. In a cross tie, a metallic end section having a substantially vertical spike-receiving recess curved laterally intermediate the ends of the recess, said recess being surrounded with material of greater hardness than the material of the main portion of the end section, the bottom or under face of the end section being hardened for increasing the strength immediately beneath the rail.

In testimony whereof I affix my signature in presence of two witnesses.

GEORGE W. VROMAN.
